UNITED STATES PATENT OFFICE.

JAMES ELLICOTT HEWES, OF NORTH CHATHAM, NEW YORK.

TUNNEL.

Application filed December 31, 1927. Serial No. 243,981.

My invention relates to tunnels, and particularly to that portion of a tunnel structure which might, perhaps, be best designated as the approach. It relates especially to approaches for vehicular tunnels which must be constructed at a considerable depth below the bottom of a river or the like, so that there is necessarily considerable difference in elevation between the tunnel proper and the entrance thereto.

In many instances where a tunnel beneath the bed of a river is highly desirable, the topography of the land along the banks of the river and the minimum possible depth of the tunnel are such that very long approaches are necessary in order to obtain a suitable grade. Again, where the natural topography is such that no unusual difficulties are presented, the land on either side of the river, under or through which the approaches must be constructed, includes closely built up portions of a city so that the cost of acquiring the necessary right of way is enormous. In such cases and many others too, an approach of such design that the entire structure can be built within two or three hundred feet of the entrance to the tunnel proper will represent a substantial reduction in the cost of tunnel construction.

The primary object of this invention, therefore, is to provide an approach occupying a minimum of ground space, which may be constructed substantially at the end of the tunnel proper, and which will provide an approach to and exit from the tunnel on substantially any desired grade. Another object is to provide an approach which may be utilized as the foundation for a building of any type so that the full use of valuable land is substantially preserved and the land, in fact, may be put to a double use.

With these objects in view my invention includes the novel elements and the combinations and arrangements of the elements described below and illustrated in a more or less typical manner in the accompanying drawings in which—

Fig. 1 is a partial, vertical section in the broken plane 1—1 of Fig. 2 of a tunnel with its approaches;

Fig. 2 is a partial, horizontal section of Fig. 1 in the broken plane 2—2;

Fig. 3 represents a portion of a helicoidal surface in which the elements are perpendicular to the linear directrix;

Fig. 4 represents a portion of a helicoidal surface, the upper part of which is concave, and in which the elements are downwardly inclined toward the linear directrix;

Fig. 5 is a fragmentary horizontal section of a modified form of approach;

Fig. 6 is a front elevation view of an approach of a somewhat different type than that shown in Figs. 1 and 2, and having entrances at different elevations;

Fig. 7 is a half-plan view of the approach shown in Fig. 6 showing a portion of the street;

Fig. 8 is a section in the plane 8—8 of Fig. 7; and

Fig. 9 is a section of the tunnel which would be used with an approach of the character shown in Figs. 6, 7 and 8.

Referring to the drawings, 1 represents the surface of the water in the river, 2 represents the bed, and 3 represents the tunnel beneath the bed of the river. In the drawings, I have shown this tunnel as level, but it is to be understood that it may be constructed on any desired grade or grades.

Where the land slopes rapidly upward from the bank of the river, or where the land is closely built up, as in a city, or in other cases if desirable, I propose to construct approaches to the tunnel proper comprising helicoidal surfaces in which the helical directrices have such a pitch as will give the desired grade. The elements of the helicoidal surfaces may be normal to the linear directrices, or may be inclined thereto at any desired angle. For example, in Figs. 3 and 4, 4 represents the plan view of a helical directrix, and 5 is the elevation view. 6 is the elevation view of the linear directrix and the plan view is the point, 7. Using these two directrices, the helical surface may be generated by, or may comprise elements, 8, which are perpendicular to the linear directrix, 6, at various points and touch or intersect the helical directrix, 5.

In order to counter-balance the centrifugal force developed by a vehicle moving around upon the surface of the helicoid, the surface may be generated by, or may comprise elements, 9, which are downwardly inclined from the helical directrix to the linear directrix, as shown in Fig. 4. This will produce a concave or "banked" helicoidal surface which is the preferred form.

In the actual construction of these ap-

proaches a central shaft, 10, of the desired diameter, is constructed. In the drawings, this shaft is shown as cylindrical but may, of course, be of almost any other desired shape. 5 Depending upon the width of the roadway desired, a second shaft or wall, 11, is constructed about the shaft, 10, and spaced therefrom a distance equal to the width of the roadway required. This outer wall or shaft 10 may be cylindrical, as shown in Figs. 1, 2, 6, 7 and 8, or it may be rectangular, as shown at 12 in Fig. 5, or any other shape. A helical directrix of the desired pitch may be imagined to exist on the interior of the cylindrical 15 wall, 11, and the helicoidal surface is generated by elements which intersect this helix and the axis, 13, of the inner shaft. The entire helicoid is, of course, not constructed but only that portion included between the 20 inner and outer shafts. Such a helicoidal surface is shown at 14.

In Figs. 1 and 2 I have illustrated this surface as making two complete turns in descending from the street level, 15, to the tunnel level, 16. In other words, a vehicle enters and leaves any approach while moving in the same direction. This, of course, is not essential, as the descent or ascent may be made at any desired grade and the entrance 30 from the street to the helicoid and the exit from the helicoid to the tunnel may be arranged in any desired manner.

Referring particularly to Figs. 6, 7, 8 and 9 I have illustrated approaches and exits at 35 different levels. In other words, instead of having a single helicoidal surface forming a comparatively wide roadway, I have shown double surfaces, one above the other which are quite analogous to what is commonly 40 known as a double threaded screw. In these figures, 17 represents the normal street level from which entrance may be had to the lower helicoid, 18. The street may be divided by a wall, 19, which will serve to retain inclined 45 approaches or ramps, 20, leading to the entrance, 21, to the upper helicoid, 22. The exits opening into the tunnel, are shown at, 23 and 24, and the tunnel itself has two passages, 25 and 26, as shown in Fig. 9.

50 If desired, openings, 27, may be provided in the central shaft to give light and ventilation. It is contemplated, however, that the approaches will be used as foundations for buildings, and where this is the case, it would 55 probably be desirable to cover the openings with glass so that noxious gases would not arise therefrom into the court of the building.

I have shown no general scheme for ventilating the tunnel and it is to be understood that any system may be used.

My preferred form of approach is shown in Fig. 5. Here, a sort of safety zone, 28, would be provided at each corner upon which 65 disabled vehicles might be run or drawn to

get them out of the way of traffic and thus avoid congestion. In this type ventilating shafts, 29, may be provided in the corners and equipped with suitable suction fans or blowers whereby the gases discharged by 70 motor vehicles may be withdrawn from the tunnel and approaches and fresh air supplied.

While I have described the general character of the roadway surface in my approaches as "helicoidal," it is to be understood that this term is used only in a descriptive sense as most nearly defining the actual structure which would be built. Where the elements of the helicoid are horizontal no difficulty will be encountered in making a smooth connection between the helicoid and the horizontal floors of the tunnel and driveway from the street, respectively. Where the elements of the helicoid are inclined to 80 the linear directrix, it will be necessary to warp in a transition surface to make a smooth connection, and this surface may be a hyperbolic paraboloid slightly modified perhaps at the juncture with the helicoid to make a 85 perfectly smooth connection.

While I have illustrated and described my invention only in its preferred embodiment, it is to be understood that the words which I have used are words of description rather 90 than words of limitation, and that changes, substantially within the purview of the appended claims, may be made without departing from the true scope and spirit of my invention in its broader aspects. 100

What I claim is—

1. The combination with a tunnel having a plurality of passages at different elevations, of approaches to said passages comprising a plurality of separate helicoidal surfaces. 105

2. The combination with a tunnel having a plurality of passages at different elevations, of approaches to said passages comprising a plurality of vertically disposed helicoidal surfaces. 110

3. A tunnel approach comprising an inner shaft, an outer shaft, and a plurality of separate helicoidal surfaces supported between said shafts to form approaches entering the tunnel at different elevations. 115

4. A tunnel approach comprising a cylindrical inner shaft, a rectangular outer shaft, and a helicoidal surface extending between and supported by said shafts to form an inclined approach to said tunnel having zones 120 of maximum width at the corners of the outer shaft.

5. A tunnel approach comprising an inner vertical shaft, an outer vertical shaft having some portions thereof spaced at greater distances from the inner shaft than other portions, and a helicoidal surface extending between said shafts to form an inclined approach to said tunnel. 125

6. The structure specified in claim 5 in 130

which the elements of the helicoidal surface are downwardly inclined toward the inner shaft; whereby a banked, circular approach to the tunnel is provided.

5. 7. A tunnel approach comprising an inner vertical shaft, an outer vertical shaft having some portions thereof spaced at greater dis-

tances from the inner shaft than other portions, and a plurality of helicoidal surfaces extending between said shafts to form separate inclined approaches to the tunnel; the elements of the helicoids being downwardly inclined toward the inner shaft.

JAMES ELLICOTT HEWES.
